UNITED STATES PATENT OFFICE.

REGINALD F. SEDGLEY, OF PHILADELPHIA, PENNSYLVANIA.

COMBINED REBOUNDING, MAIN, AND TRIGGER SPRING FOR FIREARMS.

1,216,001.

Specification of Letters Patent.

Patented Feb. 13, 1917.

Application filed June 13, 1916. Serial No. 103,368.

To all whom it may concern:

Be it known that I, REGINALD F. SEDGLEY, a subject of the King of Great Britain, residing in the city and county of Philadelphia, State of Pennsylvania, have invented a new and useful Combined Rebounding, Main, and Trigger Spring for Firearms, of which the following is a specification.

In devices of this character as heretofore manufactured, it has been customary to provide separate springs to effect the proper actuation of the trigger mechanism, the hammer and the rebound of the hammer. This increases the number of springs employed and considerable difficulty has arisen due to breakage and the difficulty which arises in tempering the springs so that they will all have the same standard of resiliency whereby a spring which is used to replace one which has been broken will have the same amount of resiliency as the one which it replaced.

In order to overcome the above and other defects arising from springs as heretofore employed, I have devised a novel spring which has a triple function since it not only serves as the trigger spring but also as the hammer spring and it is constructed in such a manner as to control the rebound of the hammer to prevent the hammer interfering with the proper revolving of the cylinder.

With the above and other objects in view which will hereinafter more clearly appear in the detailed description, my invention consists of a novel main, trigger, and rebounding spring and a novel construction of hammer, trigger, and casing adapted to coöperate with it.

It further consists of other novel features of construction and advantage, all as will hereinafter more clearly appear.

For the purpose of illustrating my invention, I have shown in the accompanying drawings, a typical embodiment of it which will give satisfactory and reliable results in practice, although it is to be understood that this embodiment is typical only and that the various instrumentalities of which my invention consists can be variously arranged and organized, and that my invention is not

limited to the precise arrangement and organization of these instrumentalities as herein set forth.

Figure 1 represents a side elevation of a fire arm, partly in section, showing a combined main, trigger, and rebounding spring, and its adjuncts, embodying my invention, certain parts being omitted for the sake of clearness of illustration.

Fig. 2 represents a side elevation, partly in section, and similar to Fig. 1, but showing certain of the parts in a different relation from that seen in said figure.

Fig. 3 represents a perspective view of the combined main, trigger and rebounding spring in detached position.

Similar numerals of reference indicate corresponding parts in the figures.

Referring to the drawings:

1 designates a frame having a grasping handle 2 which is chambered as at 3, in order to receive a combined main, trigger and rebounding spring 4 embodying my invention. 5 designates a trigger which is pivotally mounted at 6 and provided, in the present instance, with a finger piece 7 pivoted to the trigger. 8 designates a pawl pivotally carried by the trigger and adapted to effect the automatic revolution of the cylinder in the usual manner. 9 designates a spring pressed cocking pawl which effects the backward movement of a hammer 10 and is pivotally mounted on the trigger 5. The rear face of the hammer 10 is provided with an inclined face or wall 12 which connects with a curved face 13 by means of a recess 14. The spring 4 is formed from a single piece of material such as, for example, piano wire, one end 15 of which is adapted to be seated in a recess 16 in the lower wall of the chamber 3. The end 15 extends upwardly and then curves laterally, as at 17, and is then directed upwardly, as at 18, then laterally, as at 19, and then bends downwardly, as at 20, in order to form the rebounding element 21. The spring is then curved rearwardly at 22 and deflected upon itself to form a coil 23 and then curves forwardly and downwardly, as at 24, and its free end is preferably flattened to form a

95

100

forward terminal 25, which engages a groove or recess 26 in a rearward extension of the trigger 5.

The spring 4 is inserted in place so that the rear terminal 15 interlocks with the recess 16 while the forward flattened terminal 25 rests upon and interlocks with the recess 26 in the trigger. The rebounding terminal 21 is then snapped into place so that when the hammer is forward it assumes the position seen in Fig. 1 and bears against the inclined wall 12. When the hammer is retracted and the sear is ready to release the hammer 10, the spring assumes the position seen in Fig. 2.

The outer end of the terminal 21 interlocks in the recess 14 and engages the walls of said recess, as will be understood by reference to Figs. 1 and 2 and owing to the angle of the inclined face or wall 12, the terminal will have a lever action upon the hammer and since this terminal is connected by the two spring portions 22 and 17, the hammer is maintained under constant tension during the act of firing and after the firing pin 27 has engaged the cartridge, the terminal 21 will cause the rebound of the hammer away from the anvil 28 so that the parts will assume the position seen in Fig. 1. The firing pin 27 will be withdrawn a sufficient distance to permit the revolution of the cylinder.

In so far as I am aware, I am the first in a device of this character to provide a tension device which maintains a constant tension on the hammer during the act of firing and it is to be understood that my claims to such features are to be interpreted with corresponding scope.

By the employment of my novel invention, I eliminate to a marked degree the breakage of the springs and owing to the novel construction of spring one is enabled to temper them in such a manner that the springs are standard and can be readily replaced by another spring of the same type without necessitating the employment of a skilled workman. It will be apparent to those skilled in this art that in accordance with my present invention, I employ a novel construction of a tension device which maintains the hammer under tension during the act of firing or, in other words, until the trigger is released for the next shot. By altering the angle of the rebounding terminal and of the inclined wall of the hammer, the amount of rebound imparted to the hammer is correspondingly varied.

It will now be apparent that I have devised a novel and useful construction of a combined rebounding, main and trigger spring for fire arms which embodies the features of advantage enumerated as desirable in the statement of the invention and the above de-

scription, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. As a new article of manufacture, a spring consisting of an integral piece of spring wire having one end forming an abutment, its other end forming a trigger engaging portion, and having intermediate its ends a rebounding terminal.

2. As a new article of manufacture, a single spring having a coil intermediate its ends, deflected upon itself to form a rebounding terminal, and having one end forming an abutment, and having its other end forming a trigger engaging element.

3. In a fire arm, the combination with the housing, the hammer, and the trigger, of a single spring having one end engaging the housing, the other free end engaging the trigger, and an intermediate portion engaging the hammer.

4. In a fire arm, the combination with the housing, the trigger, and a hammer having an inclined face and a recess, of a single spring having one free end abutting against the housing, its other free end engaging the trigger and deflected upon itself to form a terminal normally engaging said inclined face and walls of the recess of the hammer to control its rebound.

5. In a fire arm, the combination with the housing, the trigger having a recess, and the hammer, of a single spring having one end adapted to engage the trigger recess and its other end engaging the housing, said spring intermediate its ends being deflected upon itself to form a terminal engaging the hammer.

6. A combined main, trigger, and rebounding spring for fire arms, consisting of an integral piece of spring material extending upwardly from one free end, then laterally, then upwardly, laterally and downwardly to form a hammer terminal, then rearwardly and coiled upon itself and then extending forwardly and downwardly to form a trigger terminal.

7. A combined main, trigger, and rebounding spring for fire arms, consisting of an integral piece of spring wire extending upwardly from one free end, then laterally, then upwardly, laterally and downwardly to form a hammer terminal, then rearwardly and coiled upon itself and then extending forwardly and downwardly to form a trig-

ger terminal, said trigger terminal being flattened.

8. In a fire arm, the combination with the housing, the trigger having a recess, and
5 the hammer, of a single spring having one end adapted to engage the trigger recess and its other end engaging the housing, said spring intermediate its ends being deflected

upon itself to form a terminal engaging the hammer to place a constant tension on it during the act of firing.

REGINALD F. SEDGLEY.
